ELECTRICAL PRECIPITATOR

Hans Klemperer, Belmont, Mass., assignor to Raytheon Manufacturing Company, Newton, Mass., a corporation of Delaware

Application June 20, 1946, Serial No. 678,154

5 Claims. (Cl. 183—7)

1

This invention relates to electrical precipitators for separating dust and smoke from atmospheric air, flue gases and the like, and more particularly to a circuit for energizing such precipitators.

In precipitators of the type to which the invention relates, the air or other gas to be cleaned is first ionized in a suitable ionizing device, from whence it flows through a suitable precipitating means where dust and other impurities are separated. The ionizing device comprises at least one pair of ionizing electrodes adapted to be maintained at a sufficient potential to ionize the air that passes therebetween. The precipitating means commonly comprises a plurality of spaced, parallel collector plates of substantial area between which the ionized air flows and on which the dust particles and other impurities are collected due to a difference in potential maintained between adjacent plates. The potential across adjacent plates may be of the order of 6,000 volts while the potential across the ionizing electrodes is substantially higher, for example, of the order of 12,000 volts or more.

It is among the objects of the present invention to provide a simplified circuit for supplying the desired potentials to the ionizing electrodes and the collector plates, in which circuit the collector plates function as a capacitance in a voltage-doubling circuit for substantially doubling the potential applied to the ionizing electrodes over the potential applied to the collector plates.

The above and other objects and features of the invention will be made fully apparent to those skilled in the art from a consideration of the following detailed description taken in conjunction with the accompanying drawing, in which the figure represents schematically an electrical precipitator together with a supply circuit.

Referring to the drawing, reference numeral 10 indicates an ionizing device of an electrical precipitator comprising a plurality of tubular electrodes 11 and a plurality of spaced, parallel fine wire electrodes 12, one between any two successive tubular electrodes 11, and between which tubular electrodes and fine wire electrodes an ionizing discharge is adapted to take place.

Adjacent the ionizing device 10 is a precipitating device 13 comprising a plurality of collector plates having extensive parallel surfaces and comprising a plurality of ground plates 14 and a plurality of intervening charge plates 15.

In order to supply suitable potentials between the ionizing electrodes 11 and 12 of the ionizing device 10 and a substantially lower potential between the charge plates 15 and the ground plates

2

14 of the precipitating means 13, a transformer 16 is provided having a primary winding 17, the terminals of which are connected across a suitable source of alternating current, and a secondary winding 18. One terminal of the secondary winding 18 is connected to the tubular electrodes 11 of the ionizing device and to the ground plates 14 of the precipitating means through a grounded conductor 19. A condenser 20 is connected across the terminals of the secondary winding 18 through a rectifier 21. The rectifier 21 may be any suitable rectifier such as a well-known diode. In order to avoid the necessity of providing heating circuits for the cathodes of such rectifiers, I prefer to use a glow rectifying tube such as disclosed in copending application of Paul W. Stuttsman for Gaseous discharge device, Serial No. 647,463, filed February 14, 1946 now patent No. 2,435,246, dated February 3, 1948. The anode of the rectifier is connected to the grounded terminal of the secondary winding 18, and its cathode is connected to the opposite terminal of secondary winding 18 through the condenser 20. The right-hand side of condenser 20 is thus the positive side. The positive side of condenser 20 is connected through a resistor 22, which may be of the order of 2 megohms, to the charge plates 15 of the precipitating means. The positive side of the condenser 20 is also connected through a rectifier 23 of the type described and a conductor 24 to the fine wire electrodes 12 of the ionizing device. A condenser 25 is connected between the conductor 24 and ground.

In operation, assuming, for the moment, that the ionizing device and the collector plates are disconnected, the voltage at the terminal C on the positive side of condenser 20 varies sinusoidally around $+E/2$ from 0 to $+E$ with respect to ground. With the charge plates 15 connected at A, the voltage of A varies around a center value that is closely below $E/2$. The amplitude of variation is greatly reduced being divided between the resistive and capacitive components. A large resistance cancels more of the ripple and develops less heat. However, if the resistance is too large, it may unduly limit the short-circuit current between the plates. In a small unit suitable for household use, where the capacity of the plates was $0.01\mu F$, I have found that a resistance of two megohms is desirable. With such a resistance the ripple voltage is limited to ± 1000 volts at 5900 volts. Thus the peak voltage applied to the collector plates is not excessive, nor is the minimum voltage so low as to prevent con-

tinuous effective operation of the precipitating unit.

The operating resistor loss in this instance is about one watt, and the sustained short-circuit current through the plates and the same resistor is 3 ma.

The voltage applied at B is substantially equal to +E relative to ground. This voltage which is applied across the ionizing electrodes 11 and 12 is approximately twice that applied to the precipitator plates, and is, therefore, of the order of 12,000 volts. This voltage is sufficient to cause an ionizing discharge to ionize the air or other gases passing through the ionizing device in the direction of the collector plates where the dust, smoke and similar impurities are precipitated.

While there has been herein described a preferred embodiment of the invention, other embodiments within the scope of the appended claims will be obvious to those skilled in the art from a consideration of the form shown and the teachings hereof.

What is claimed is:

1. An electrical precipitator for purifying gas comprising ionizing electrode means, a plurality of spaced, parallel collector plates comprising alternate charge and ground plates upon which impurities in said gas are collected, a source of alternating current, circuit means for deriving a unidirectional pulsating potential from said source, and circuit means including a resistor in series with said collector plates connected to an intermediate point of said pulsating potential deriving means whereby to employ the capacitance inherent in said collector plates for deriving a potential from said pulsating potential of approximately the average value of said pulsating potential for energizing said collector plates, and means providing substantially the entire pulsating potential to said ionizing means.

2. An electrical precipitator for purifying gas comprising a plurality of ionizing electrodes between which an ionizing discharge is adapted to occur, a plurality of spaced, parallel collector plates comprising alternate charge and ground plates upon which impurities in said gas are collected, a source of alternating current, circuit means for deriving a unidirectional pulsating potential from said source, circuit means including a resistor and the capacitance inherent in said collector plates for deriving a potential from said pulsating potential of approximately the average value of said pulsating potential for energizing said collector plates, and means for deriving a second potential from said pulsating potential approximately equal to the peak value of said pulsating potential for energizing said ionizing electrodes.

3. An electrical precipitator for purifying gas comprising a plurality of ionizing electrodes between which an ionizing discharge is adapted to occur, a plurality of spaced, parallel collector plates comprising alternate charge and ground plates upon which impurities in said gas are collected, a source of alternating current, circuit

means for deriving a pulsating potential varying between zero and a predetermined value in one direction from said source, circuit means including a resistor and the capacitance inherent in said collector plates for deriving a potential from said pulsating potential of approximately one-half of the peak value of said pulsating potential for energizing said collector plates, and means for deriving a second potential from said pulsating potential approximately equal to the peak value of said pulsating potential for energizing said ionizing electrodes.

4. An electrical precipitator for purifying gas comprising a plurality of ionizing electrodes between which an ionizing discharge is adapted to occur, a plurality of spaced, parallel collector plates comprising alternate charge and ground plates upon which impurities in said gas are collected, a source of alternating current, a circuit including a rectifier and a condenser for deriving a unidirectional pulsating potential from said source, circuit means including a resistor and the capacitance inherent in said collector plates, for deriving a potential from said pulsating potential of approximately one-half of the peak value of said pulsating potential for energizing said collector plates, and means including a second rectifier and a condenser for deriving a second potential from said pulsating potential approximately equal to the peak value of said pulsating potential for energizing said ionizing electrodes.

5. An electrical precipitator for purifying gas comprising a plurality of ionizing electrodes between which an ionizing discharge is adapted to occur, a plurality of spaced, parallel collector plates comprising alternate charge and ground plates upon which impurities in said gas are collected, a source of alternating current, a circuit including a rectifier and condenser for deriving a pulsating potential varying between zero and a predetermined value in one direction from said source, circuit means including a resistor and the capacitance inherent in said collector plates for deriving a potential from said pulsating potential of approximately one-half of the peak value of said pulsating potential for energizing said collector plates, and means including a second rectifier and a condenser for deriving a second potential from said pulsating potential approximately equal to the peak value of said pulsating potential for energizing said ionizing electrodes.
